PHONOGRAPH DICTAPHONE COMMUNICATION APPARATUS

Filed Sept. 22, 1928

UNITED STATES PATENT OFFICE

GEORGE R. COOPER, OF UPPER DARBY TOWNSHIP, DELAWARE COUNTY,
PENNSYLVANIA

PHONOGRAPH-DICTAPHONE COMMUNICATION APPARATUS

Application filed September 22, 1928. Serial No. 307,712.

This invention relates to improvements in sound recording apparatus and more particularly to telephone-operated mechanism for conveying messages over the phone after 5 said messages have been recorded for telephone transmission purposes and this application is a companion to my co-pending application #309,196 filed September 22, 1928.

One of the objects of my invention is to 10 provide a simple, efficient and inexpensive device designed to convey automatically over the phone a message when a distant caller rings up to converse with a telephone user and this user is out of his office. This present 15 invention relates to a type of invention disclosed in a copending application wherein devices are shown for conveying the messages automatically over the phone.

Another object of my invention is to 20 provide, in a telephone operated apparatus for conveying recorded messages, improved means for dictating messages locally to be delivered through the telephone instrument to distant callers.

25 A further object of my invention is to provide apparatus for recording the message dictated over the phone by a distant caller through the telephone instrument of an absent user.

30 A still further object of my invention is to provide means without speaking tubes in a device as described, for recording messages and letters locally to be heard locally, producing results of dictating machines in common use.

35 With the above and other objects in view my invention consists in the combination, arrangement and details of construction disclosed in the drawings and specification, and 40 then more particularly pointed out in the appended claims.

In the drawings, wherein similar reference characters designate similar parts throughout the respective views,

45 Fig. 1 is a side elevation, partly in section of the parts of my invention.

Fig. 2 is a fragmental detail view of a message stop device.

50 Fig. 3 is an end elevation, partly in section, of the parts of my invention.

Fig. 4 is a side elevation of solenoid 69d.

Fig. 5 is a detail view of a bell clapper arm.

Fig. 6 is a side elevation of a device for returning machine to normal or initial position.

55

Fig. 7 is a side elevation of solenoid 69.

Referring to the drawings, which are merely illustrative of my invention details are disclosed supplementing the disclosure of an invention for automatically and telephonically recording and conveying messages during the absence of a telephone user. Reference will be made to a copending application directed to the same physical parts but descriptive particularly of the details concerning closing the circuit to the message conveying apparatus automatically. Herein it is proposed to disclose the details as they relate to the manner in which the message is dictated for transmission locally to distant points and for recording the messages locally impressed upon the same apparatus.

60

In practice, in a telephone box 11, mounted upon a post 10, are located the bell clapper C whose clapper stem B is designed to ring the bell A when the telephone is put into use in the conventional way. The means for operating the clapper is through the lever E pivotally connected loosely and with lost motion permissible, to the clapper C as at 70 75 79m. The upper end of the lever E is pivotally connected to the armature 83 having a pivotal movement upon the switch member W insulatedly connected to box 11. An electromagnet 18 is mounted in the box 11, as also is 80 85

a fixed contact member 25 having a binding post 26. A coiled spring 24 is secured to the armature and to a point of the box and normally holds this armature in contact with two contacts 67d and 67, the armature being divided into two circuit making portions 23, 88 by means of the insulation 82. One of the line wires 19 is connected to magnet 18, the other wire 17 connecting to this magnet also connecting with binding post 16 of the transmitter box.

90

The other line wire 26 may be connected with binding post 15 if desired (not shown).

The receiver 13 hangs upon its hook, and the transmitter 14 is also disclosed. A bat- 95 100

tery 29 has a wire 28 running from one side thereof to wire 27 to the contact 25. A knife switch handle 61 has its blade engaged in the switch member W and this blade is pivoted 5 to a curved contact member 65c carrying a binding post 65d with which the blade of the switch 61 may also engage. From binding post 65d leads a wire 21g to the other side of battery 29, and from this side of the battery 10 runs a wire 30 to a binding post 31 on a motor base M on which is mounted a motor 35 having a shaft 36 carrying a pulley on which is trained a belt 37 which is also trained upon a pulley 38 on a main shaft 39 journalled 15 in a standard or upright 57. The other binding post 32 of this motor base has the wire 64' running to connect with contact post 65a. A pair of oppositely arranged wax cylinders 40, 40a are mounted upon the opposite ends of the shaft 39.

A series of hook-shaped contacts 41 are provided and their shanks 43 are designed to be carried by collars 42a adjustably slideable upon a rod 42 raised above the base M by 25 means of the legs 43 secured to this base M. These contacts 41 are spaced apart at varying distances for the purpose of setting apart spaces therebetween upon which messages can be recorded upon the wax cylinder 40, longer 30 messages requiring greater spaces between the contacts 41.

A lever or pendant 55 is pivoted between its ends upon a pin 56 to the upright or standard 57, and at its ends respectively carries 35 the pins 54 and 54' designed to freely project in the slots 53 and 53' of hangers 52 and 52' secured centrally upon rectangular frames 51 and 51a, these frames providing tiltable bracket spiders. Mounted upon the 40 lower rung of bracket spider 51 at the left of Fig. 1 is an operatively mounted transmitter receiver 46, a similar device 46a being shown on the spider 51a on the right of Fig. 1.

The recorder-reproducers 46 and 46a are 45 adjustably mounted upon the bracket-spiders carrying them, the stops 49h, 97 and 100 limiting movement of these members upon the spider. From contact post runs a wire 89' to contact post 48a on the recorder-reproducer 46a, and from the other contact post 49a of this member runs wire 90a and wire 21k to wire 21a, wire 21 to contact 15 via wires 21p, armature 23 and wire 21c, and the adjacent contact 16 has wire 17 connected 55 thereto which runs to electro-magnet 18 from which runs the wire 19 as one of the telephone line wires. A wire 21g runs from contact post 65d of the switch 61 and connects with wire 30 running from one side of the battery. Wire 21e runs from contact 82 on 60 contact arm 80b and connects with wire 28 which runs to the other side of the battery; while wire 33 runs from the other contact arm 81 to the motor 35 (see Fig. 3). The 65 wire 21d connects telephone 77 and wire 21e.

A wire 46m runs from wire 68 (see Fig. 6) to binding post 46g mounted on stop 46h from which post wire 46n runs to post-contact 46, which is immovably mounted upon stop 46h. Contact 46j is mounted upon a stem 70 which projects through 46h. Contact 46j is mounted upon a stem which projects through a hole in 46h being pressed against recorder-reproducer 46 by spring 46i. Wire 46k runs from 46j to post 46p on rod 43. Means in common use with necessary modifications will be employed to move recorder-reproducer on the cylinders. 75

From binding post 66 runs wire 68 to binding post 80 on conductor 79 of solenoid 69 (see Fig. 7). Insulation 78 separates conductor 79 from arm of plunger-armature 76. Contact arm 72 is insulated from support 70 which support is part of standard 88. Wire 68c runs from binding post 73 to solenoid 69 80 from which runs wire 74f to wire 74d which wire connects with contact 74c upon which rests contact 74b when microphone 77 is resting on arm 80b. From contact 74c runs wire 74e to 74r to binding post 74q, (see Fig. 4), 85 contact 74p. The circuit continues to conductor shoe 85, stem 87, wires 74m and 74 to battery 29.

From the battery 29 runs wire 30 to which is connected wire 69c which runs to post 80a of solenoid 69a (see Fig. 4). Contact arm 79a is insulated from arm plunger 76a by insulation 78a. Conductor arm 72a is insulated from casing 70a from which casing extends also arm 84 which supports shoe 85, its stem 87 and spring 86 which presses 85 against plunger 76a. Wire 68b connects binding post 73a to solenoid 69a and wire 74a leads from the solenoid to wire 74e. 95

The magnets controlling the posts 76 and 76a are for the purpose of lowering one end of the bracket-spider or teeter to depress one recorder-reproducer to engage with one wax cylinder while the other recorder-reproducer is raised out of engagement with the other cylinder. 100

From the foregoing description the operation of the parts will now be described.

When it is desired to record messages of varying character upon the cylinder 40, which is for transmitting messages over the phone to parties calling while a person is absent, the person talks into the transmitting instrument 77 the particular message it is desired to record upon this cylinder. See that switch W is open and that switch 65c is closed. 110 (Fig. 1).

Place recorder-reproducer 46 on the proper section of the cylinder 40, by lifting lever or frame 55, adjusting the stops 46h and 98 on the spider, and then lowering the frame 55 to place the needle 60 upon the record cylinder 40. Take the receiver-transmitter 77 off the hook 79 of contact lever 80b to allow the former to spring up automatically against 125 the latter.

contact 81, to close the motor circuit. As the frame 55 is lowered, the armature plunger 76 of solenoid 69 is lowered also and held down in this position by the pressure of the spring-pressed brake shoe 85 attached to solenoid 69a. The motor circuit is closed as follows: contact 81 to binding post 34, to wire 33, through motor to wire 30 to battery 29, through wires 28, 21e to the binding post 82, contact 80b, and back to contact 81, as the latter has engaged contact 80b when the receiver 77 was removed from its hook. The operator may then speak a message through receiver-transmitter to recorder-reproducer 46 as follows:

"Hello, Blank and Company speaking. The office is closed now as our hours are from 9 a. m. to 4.30 p. m. If you cannot call up in the morning please leave your message."

The person calling thus receives this message, when central telephone station establishes the connections properly. The present invention can be efficiently employed to record a conversation over the phone while the owner himself is phoning. In this event it will be necessary to push down the spider and frame 51a, to place the needle 60a in contact with the adjacent wax cylinder 40a. Then switch W will be closed and armature 23-83 depressed. This will close the circuit to the motor as follows:—While the distant telephone instrument is in use by one of the parties talking, current flows from one side of battery 29, through wire 30, to motor 35, wire 64', binding post 63, thence through closed switch 61, armature 23-83, post 25, wire 27 and connecting wire 28 back to the other side of the battery 29.

The motor starts to rotate both cylinders and needle 60a, at the right of Fig. 1, begins to trace the conversation upon the adjacent wax cylinder 40a. When the conversation has been completed it will be necessary to open switch 61 again.

The phone circuit for this operation is as follows: electro-magnet 18, line wire 19, central operator, distant telephone, central, line wire 26, wire 21g, armature 23, wires 21p, 21, 21k, 90a, recorder-reproducer 46a, wires 89' and 21c, post 63, switch 61, armature 83, contact-post 25, wires 27 and 21b, post 16 and wire 17 back to magnet 18.

The method of hearing messages dictated to a wax cylinder 40a for recovery by a stenographer or typist and for hearing messages received when the owner may not be present will now be described. See that the switch W is open and 65c closed. Place receiver-transmitter 77 to the ear and see that the needle 60a rests upon the wax cylinder 40a and that the post 49a rests against stop 100 (Fig. 1). This will close the motor circuit as follows:—The removal of instrument 77 from the contact arm 80b causes this contact

to abut contact 81; current flows from one side of the battery 29 by wire 30 to motor 35; thence by wire 33 to contact 81; thence by wire 21e and wire 28 back to the other side of the battery. The phone circuit between receiver-transmitter 77 and recorder-reproducer 46a is closed as follows: phone 77, wires 21d', contacts 21s and 21t, wires 21d, 21e, 28 through battery 29 and wire 21g, switch 65c, post 65a, wires 21c and 89', post 48a, recorder-reproducer 46a, post 49a, wires 90a, 21, 21a, phone 77.

In order to dictate messages for the typist using the invention as a dictating machine proceed as described hereinbefore in connection with employing the receiver-transmitter 77 to hear a recorded message. Be sure that the needle of the recorder-reproducer 46a has been placed beyond the last indented line on the wax cylinder 40a marking the end of the next previous message, which point is indicated by movable slide tab 101. Talk into the transmitter 77 instead of applying it to the ear.

In order to dictate messages in answer to prospective calls see that switch W is open; close switch 65c. Place the receiver-transmitter 46 at the left of Fig. 1 in the correct position or section of the record cylinder 40 so that its needle 60 will ultimately engage the proper hook contact 41, lifting bracket frame 51 in order to effect this result. The operation then proceeds in a manner already detailed hereinbefore, the motor circuit being the same.

The phone circuit is as follows: phone 77, wire 21d, contacts 21s and 21t, wires 21d and 21e, 28, battery 29, wire 21g, switch 65c, post 65a, wires 21c and 89, post 48, recorder-reproducer 46, post 49, wires 90, 21, 21a and back to phone 77. From the foregoing it will be seen that messages may be heard locally that are dictated locally.

It is understood that ordinary gears and worms, etc., from shaft 38 will control the movement of recorder-reproducer 46 and 46a upon the wax records.

Having described my invention, I claim:

1. In apparatus of the character described, the combination of a plurality of record holders, means for rotating said record holders, recording and reproducing means positioned in cooperative relation with records on the respective record holders, and supporting mechanism for said means comprising a fulcrumed lever tiltable to disengage one of said means from its record when the other of said means moves toward its record and means comprising an electrical circuit controlled by the rocking of said lever for operating said lever.

2. In apparatus of the character described, the combination of a plurality of record holders, means for operating said record holders, styluses positioned for cooperation with rec-

ords carried by the respective holders, means for supporting said styluses comprising a fulcrumed lever, frames pivotally connected with the opposite ends of said lever, and dia-

5 phragms connected with said frames and supporting said styluses, said diaphragms being movable longitudinally along said frames independently of one another.

3. In apparatus of the character described, 10 the combination with a plurality of record holders, means for operating said record holders, a rocking frame-work, styluses carried by said frame-work, said frame-work being oscillatable to move one of said styluses 15 into contact with a record on one of said holders and simultaneously move the other of said styluses from a record on the other of said holders, and means controlled by the movements of one of said styluses for effecting the 20 rocking of said frame-work.

4. In apparatus of the character described, the combination with a plurality of record holders, means for operating said record holders, a rocking frame-work, means comprising styluses for recording on and reproducing from records carried by said holders, said means being carried by said frame-work and rocked thereby, mechanism controlled by 25 one of said means for rocking said frame-work, and means for reversely rocking said frame-work, said means last named comprising electromagnetic mechanism and a telephone circuit controlling said electromagnetic mechanism.

30 35 In witness whereof he has hereunder set his hand this 5th day of July, 1928.

GEORGE R. COOPER.
